UNITED STATES PATENT OFFICE.

LENDIS FREDRICK DAHL, OF SNOHOMISH, WASHINGTON.

BILLIARD-CUE-CHALK HOLDER.

965,414.

Specification of Letters Patent. Patented July 26, 1910.

Application filed January 7, 1908. Serial No. 403,704.

To all whom it may concern:

Be it known that I, LENDIS F. DAHL, a citizen of the United States, residing at Snohomish, in the county of Snohomish 5 and State of Washington, have invented a new and useful Billiard-Cue-Chalk Holder, of which the following is a specification.

This invention relates to a device for holding billiard cue chalk; and has for its object 10 to provide a simple, efficient and convenient article of this character which is to be carried by a billiard player in the palm of that hand serving as the cue rest, and attached loosely to the middle finger by a ring rigidly 15 fastened to the holder and brought into operative position between the thumb and middle finger to expose the chalk by a movement of the thumb.

Another object of the invention is to provide in connection with the chalk holder, 20 means for holding an exposed filing or abrading plate or sheet for roughening the tips of billiard cues when, through use and otherwise, they become hard and smooth 25 and refuse to take the chalk.

With these and other objects in view the invention consists of the novel construction combination and arrangement of parts hereinafter described and definitely claimed, 30 reference being had to the accompanying drawing, in which—

Figure 1 is a perspective view of the chalk holder in its preferred form; Fig. 2 is a longitudinal central sectional view of 35 the same; Fig. 3 is a perspective view of a metal disk with a file cut face for roughening cue tips; Fig. 4 is a similar view of a piece of sand paper for the same purpose; Fig. 5 is a view of the chalk holder in use, 40 and Fig. 6 is a perspective view of a modified form of the chalk holder.

Similar reference numerals are used for the same parts in all the figures.

The holder in its preferred form comprises 45 a cylindrical case 1 of a diameter such as will admit a block of billiard chalk 2 of similar shape and usually, with sufficient friction to hold it in place but should the chalk block be a little small, a spring 3 is 50 provided which may be attached to or made integral with the cylinder 1 and project through an opening 4 in the side thereof, as shown, to bear on the outer surface of the chalk block.

55 One end of the cylinder 1 is left open for inserting the chalk and the cue tip, the other

end is also open but surrounded by a narrow inturned flange 5 against which bears a thin plate 6 having its outer face made abrasive or file cut for roughening the tips 60 of billiard cues when they become smooth and hard. In place of the file plate 6 a disk of sand paper 7 or other suitable material may be employed. The file plate or sand paper disk is held in place by the back of 65 the chalk block bearing against it.

Secured to the outer surface of the chalk cylinder 1 is a ring 8 radially disposed with relation to the cylinder, and having its axis at a right angle to the axis of said cylinder. 70

As thus constructed, when a person starts to play billiards and other games requiring a chalked cue, the ring 8 of the chalk holder is slipped over the middle finger of the left hand (or the hand which forms the cue 75 rest), with the cylinder on the palmar side and the open chalk end directed toward the little finger. The hand may be closed or arched over the chalk holder in any of the peculiar ways known to billiardists for 80 forming the cue rest, without inconvenience and with the knowledge that the chalk is always at hand and easily moved into position for use by placing the thumb on the chalk holder and turning it around the middle finger as represented in Fig. 5. Then 85 grasping the chalk holder between the thumb and middle finger it will be held firmly and ready for use. If the tip is to be roughened, the chalk holder is removed from the finger 90 and the abrasive end applied to the cue tip, but as this occurs so seldom compared with the constant use of chalk, it will not be considered an inconvenience to slip the ring 95 from the finger. In actual use, the middle, fourth and little fingers will be flexed around the cue and not, as in Fig. 5, extended to show the invention to better advantage.

While the chalk holder or case 1 has been 100 described above as of cylindrical form, this shape is not essential. In Fig. 6 the case 1 is shown in square form to hold cubical chalk blocks, it may also be made hexagonal, octagonal or in whatever cross sectional 105 shape the chalk is molded or pressed.

It will be understood that when it is desired to remove the block of chalk from the holder, for example, when the block has become considerably worn, the little finger or 110 the tip end of the cue may be inserted through the opening in the end 5 of the

holder and pressure brought to bear upon the chalk block whereby to eject it from the holder.

What is claimed is:

- 5 1. A chalk holder comprising a casing having openings in opposite ends, one opening being for the insertion of a chalk block, said casing having an opening formed also in one side, and a spring tongue carried by 10 the said side and projecting through the opening and adapted to bear against the side of the said block of chalk, the said tongue having its free end projecting toward that end of the casing opposite that through 15 which the chalk is inserted, and a ring secured to the said casing.

2. A chalk holder comprising a casing having openings in opposite ends, one open-

ing being for the insertion of a chalk block, the said casing having an opening formed 20 also in one side, and a spring tongue stamped from one side of the casing and integral therewith and projecting through the said opening and adapted to bear against the side of the said block of chalk, the free 25 end of the tongue being projected toward that end of the casing opposite that through which the chalk is inserted, and a ring secured to the said casing.

In testimony that I claim the foregoing as 30 my own, I have hereto affixed my signature in the presence of two witnesses,

LENDIS FREDRICK DAHL.
